(57) CLAIM

The ornamental design for a pen cover for pull reel, as shown and described.

DESCRIPTION

FIG. 1 is a perspective view of a pen cover for pull reel embodying my new design;

FIG. 2 is a top plan view thereof;

FIG. 3 is a bottom plan view thereof;

FIG. 4 is a front elevational view thereof, the rear elevational view being a mirror image thereof; and,

FIG. 5 a left side elevational view thereof, the right side elevational view being a mirror image thereof.

The broken lines showing inside and top surfaces of the pen cover for pull reel in FIGS. 1-3 are included for the purpose of illustrating environment and form no part of the claimed design.
